FRANK E. JONES, OF PAWTUCKET, RHODE ISLAND, ASSIGNOR TO HEMPHILL COMPANY,
OF CENTRAL FALLS, RHODE ISLAND, A CORPORATION OF MASSACHUSETTS.

KNITTED GLOVE AND METHOD OF MAKING THE SAME.

1,413,537.

Specification of Letters Patent. Patented Apr. 18, 1922.

Application filed April 30, 1919. Serial No. 293,692.

To all whom it may concern:

Be it known that I, FRANK E. JONES, a citizen of the United States, and a resident of Pawtucket, in the county of Providence and State of Rhode Island, have invented an Improvement in Knitted Gloves and Methods of Making the Same, of which the following description, in connection with the accompanying drawings, is a specification, 10 like characters on the drawings representing like parts.

This invention relates to a knitted glove and method of making the same.

It is the object of this invention to provide a knitted glove wherein certain parts are composed of strips of fabric produced by reciprocating knitting, the edges of said strips being reinforced by specially formed selvages thereby to provide stronger and 20 more uniform edges for supporting the stitches of the seams which unite the edges of said strips.

Referring to the drawings wherein are disclosed merely for purposes of illustration 25 gloves embodying the essential features of the invention,—

Fig. 1 is a perspective view of a glove blank constructed in accordance with the invention;

30 Fig. 2 is a front elevation of another form of glove embodying the characteristics of this invention; and

Fig. 3 is a diagrammatic plan view of a portion of one of the selvages illustrating the 35 formation of the loops thereof upon a greatly enlarged scale.

In the drawings, referring more particularly to Fig. 1, there is illustrated a glove formed entirely by reciprocating knitting 40 consisting of a strip of fabric including front and back hand coverings 1 and 2, which hand coverings are united by a plurality of strips 3, 4, 5 and 6 of fabric constituting the digit strips of the glove and which are knitted integral with said front and back hand coverings. The strips 3, 4, 5 and 6 are each formed by reciprocating knitting substantially double the length of their respective fingers, and in the present instance these 45 strips are shown fashioned midway of their length in any suitable manner, as by the usual narrowing and widening, to provide tapered finger tips capable of more readily conforming to the ends of the fingers of the hand, said 50 fashioned portions being illustrated at 3',

4', 5' and 6' of the four finger strips, respectively.

Connected with the front hand covering 1 of the strip, there is also shown a strip of fabric 7 constituting the thumb strip, and 60 this strip is herein knitted integral with said hand covering double the length of the thumb and has a fashioned tip 7' similar to the tips of the fingers hereinbefore described. Each of said digit strips being 65 formed by reciprocating knitting has a selvage or reinforced edge *a* at each side thereof, and the front and back hand strips 1 and 2 being likewise formed by reciprocating knitting also have similar selvaged edges 70 along opposite sides thereof, and these edges, as in the case of the edges of said finger strips, are subsequently seamed together to complete the formation of the glove.

It is to be distinctly understood that the 75 invention is not limited to the particular type of glove herein shown and it is within the scope and purpose thereof to employ any type of blank embodying a strip or strips of fabric formed by reciprocating knitting. 80 For example, in Fig. 2 a glove blank of quite a different character is illustrated, yet it embodies substantially all of the principal features of the invention. In this blank the hand portion 8 is a tubular web formed by 85 rotary knitting and extends from the edge 9 of the wrist to the base-line 10 of the fingers. Formed integral with said tubular hand 8, is a thumb strip 11 herein similar to the thumb strip 7 of the blank previously described. This strip is likewise substantially 90 double the length of the thumb and, as herein shown, the tip 12 of said strip is fashioned so as to more readily adapt itself to the form 95 of the thumb.

As distinguished from the construction of the finger strips of the previous blank, the finger strips of Fig. 2 are each of finger length and knitted reciprocatingly integral with the hand section 8, the first finger strip 13 thereof being double the width of the finger and oppositely selvaged at *a'*, *a'* upon the inside of the finger. The second finger covering 14 is composed of front and back strips 16 and 17, respectively, which are likewise 100 formed by reciprocating knitting to produce selvaged edges *a'*, *a'* at opposite sides thereof, these strips being single width strips as distinguished from the strip 13. The third finger covering 15 is likewise formed recipro- 105

110

catingly in two sections 18 and 19 constituting the front and back coverings for said finger, thus producing oppositely selvaged edges a' , a' . The fourth, or little finger is 5 formed similar to the first finger. That is, said fourth finger covering is a double width, reciprocatingly knitted strip constituting the front and back coverings 20 and 21, the two sections thereof being integrally united at the 10 outside of the finger and oppositely selvaged at a' , a' , which edges lie upon the inside of the finger. The finishing of the gloves hereinbefore described is effected by the stitching together of the adjacent selvages a , a and 15 a' , a' , respectively, of the two types of blanks hereinbefore described.

In order to produce a neat and durable glove, it is desirable that the selvage edges of the various strips of the blanks be even 20 and relatively stronger than the fabric to adequately support the stitches of the seams formed by uniting adjacent edges of said strips. It is with such objects in view that the present invention has been provided, 25 and in the carrying out of the same a rotary-reciprocatory knitting machine is preferably, though not essentially, employed, upon and by which are formed the selvaged or reinforced edges a and a' consisting of inter-engaged loops approximating twice the 30 length of the regular loops 29 of the strips at the edges whereof said selvages are formed, and these selvages are adapted to be produced along each edge wheresoever a selvage is required to provide the necessary 35 support for the stitches of which the seams uniting the adjacent edges of the strips are composed.

Fig. 3 illustrates a section greatly enlarged of any one of the selvaged strips of either type of blank hereinbefore described. The selvages of said strip, as indicated at 25, 25, herein comprise continuous series of units 26, 26 formed at opposite edges of the 40 strip, and each is composed of a relatively large, complete loop 27 and a relatively large, partial loop 28 formed from the same yarn that is employed in the formation of the regular loops 29 of the fabric and approximating twice the size of said loops 29.

The strip at the edges whereof said selvage-forming or reinforcing loops are disposed, is composed of partial courses 30, 31, 32, etc., the yarns thereof extending alternately from edge to edge of the strip. That 45 is, the course 30 will be formed by one reciprocal movement of the machine, that is with the needles moving in the direction of the arrow b , and the course 31 will be 50 formed while the needles of the machine are moving in the reverse direction to that indicated, said courses 30 and 31 being united, in the present instance, at the left-hand side of the strip of Fig. 3 by one of the units 55 composed of the complete loop 27 and the

partial loop 28, while the courses 31 and 32 are likewise united at the right-hand side of said section by a unit also composed of a complete loop 27 and partial loop 28. Thus a series of interengaged loops will be formed 70 of double yarns approximating twice the size of the ordinary loops 29 of the fabric and forming a reinforced series of loops along each side of said strip.

A desirable method of forming a glove 75 blank having oppositely reinforced selvaged edges, as hereinbefore described, consists in knitting either reciprocatively or rotatively upon a series of needles, according to the type of glove blank that is to be used, then 80 in knitting upon selected groups of said needles integral with the fabric previously formed and in any desired sequence, a plurality of digit strips and in forming upon the end needles of said groups complete and 85 partial loops 27 and 28, and then in effecting the inter-engagement of said loops 27 and 28 with the next similarly formed loops of said needles. In other words, the machine, upon which the blank is to be formed, if 90 said blank is of the type shown in Fig. 1, will be operated reciprocatively to produce either the front or the back hand strip 1 or 2, according to the point in the glove where knitting is started. If the front is knitted 95 first, the entire group or series of needles of the machine will be employed, and during the first movement of said series the first needle of said series will, during its movement toward the knitting cams, be raised by 100 suitable instrumentalities, such as a narrowing picker, to its inoperative position to pass by said knitting cams without being operated thereby. Consequently the loop which 105 was previously formed upon said first needle, that is the complete loop 27, will be held over one movement of its group of needles, and as said needle passes the yarn feeding means a new yarn will be laid partly therearound to form the partial loop 28. The 110 second needle of the set will pass into the knitting cams together with all of the needles of said series following thereafter and function in the natural way to produce new loops and to cast off the old loops thereof. 115 During the reverse movement of the needle cylinder, the last needle of said series which was the first in the previous movement, will at the proper time be restored by suitable means, such as a specially constructed widening picker, into its operative position so as to 120 function naturally when passing said knitting cams to form a new and complete loop 27 and to cast therefrom the complete and partial loops 27 and 28 previously formed 125 upon said needle.

When the needles move in the direction of the arrow b to form said course 30, the last needle of said series will, as previously stated, pass through the knitting cams and

function naturally to produce a complete loop 27, but upon the next reverse movement of said series of needles, said last needle will now become the first of the series and in approaching the knitting cams will be raised by any suitable means, such as a narrowing picker, to pass over said knitting cams so as not to be operated thereby; but in passing said cams and the yarn-feeding means thereof, a new yarn will be laid partly around said first needle and form the partial loop 28 upon said needle with the complete loop 27 previously formed thereon.

All of the needles following thereafter, including the needle which was first in the preceding movement of the series, will pass through said cams and function naturally to form new loops.

The subsequent movements of the needle carrier with the series of needles thereon result in the formation of similar units composed of complete and partial loops 27 and 28, which units are inter-engaged to form a continuous chain of loops along each side of the hand strip, and by reason of the fact that the loop upon said needles is held over one movement of the cylinder without casting off, the loops so formed will approximate twice the length of the regular loops of the fabric, and these loops will be composed of double yarns, thereby providing ample support for the stitches whereby the edges of said strips are seamed together.

In a like manner may be formed the selvaged or reinforced edges of each and every strip, whether thumb, digit or hand strip of the glove.

While I have herein shown and described for illustrative purposes certain embodiments of my invention, and have disclosed and described in detail the construction and arrangement incidental to such disclosures, it is to be distinctly understood that the invention is limited neither to the mere details or relative arrangement of parts, nor to the specific applications shown, but that numerous substitutions and alterations may be made without departing from the principles thereof.

50 I claim—

1. In a knitted glove, a strip of fabric provided with a selvaged edge consisting of double, inter-engaged loops approximating twice the length of the loops of said strip.

2. In a glove, a knitted web having oppositely selvaged edges consisting of a continuous series of relatively large double loops.

60 3. In a knitted glove, a plurality of digit strips each consisting of partial courses composed of yarn extending alternately from edge to edge of said strips, and a series of relatively large, inter-engaged partial and complete loops formed at opposite edges of

said strip from successive course-connecting sections of said yarn.

4. In a knitted glove, a hand covering, and a plurality of selvaged digit strips formed integral with said hand covering, the selvages of said strips consisting of a series of inter-engaged units each composed of partial and complete loops and substantially double the size of the regular loops of said strips.

75 5. In a knitted glove, a hand covering, and a plurality of selvaged thumb and finger strips formed integral with said hand covering, the selvages of said strips consisting of a series of inter-engaged units each composed of partial and complete loops substantially double the size of the loops composing said strips.

80 6. A machine knitted flat web having selvages formed along opposite edges composed of relatively large, double loops formed from successive course connecting sections of the yarn, one of said double loops being connected through the closed end of a previously formed selvage loop with one of the courses of the fabric, the other of said double loops being connected at the throat end of a subsequent selvage loop with a successive course of the fabric.

85 7. In a knitted glove, a hand covering and a plurality of selvaged digit strips formed integral with said hand covering, the selvages of said strips consisting of a series of inter-engaged units, each composed of partial and complete loops having connection respectively through subsequent and preceding loops of said selvage with successive courses of said strip.

90 8. That method of forming a glove which consists in knitting a strip of fabric constituting a hand covering, then in knitting a series of narrow strips of fabric integral with said hand covering constituting digit strips, and in forming from successive course-connecting sections of yarn a partial and a complete loop both of which are interknitted with similar loops of the next course-connecting section of yarn.

95 105 9. That method of forming a glove which consists in knitting a strip of fabric composed of partial courses and, during the formation thereof, in knitting from successive course-connecting sections of yarn, a partial and a complete loop and in interknitting said partial and complete loops with similar loops formed from successive course-connecting sections of yarn, then in knitting a plurality of overlapping digit strips integral with the first-mentioned strip and forming, during the knitting of said digit strips, partial and complete loops from the course-connecting sections of yarn of said strips interengaging with similar loops of successive courses to form reinforced selvaged edges.

110 120 125 130 10. In a knitted glove, a strip of fabric

having a selvaged edge composed of relatively large interengaged partial and complete loops formed from successive course-connecting sections of yarn of which the 5 loops of said strip are formed.

11. In a knitted glove, a strip of fabric having a selvaged edge composed of relatively large interengaged partial and com-

plete loops approximating twice the size of the regular loops of the fabric and formed 10 from successive course-connecting sections of yarn.

In testimony whereof, I have signed my name to this specification.

FRANK E. JONES.
